C. W. WITT

LAUNDRY TUB

Filed Feb. 28, 1920

Inventor

C. W. Wizz

By *Watson E. Coleman*
Attorney

UNITED STATES PATENT OFFICE.

CLARENCE W. WITT, OF WHEELING, WEST VIRGINIA.

LAUNDRY TUB.

Application filed February 28, 1920. Serial No. 362,036.

To all whom it may concern:

Be it known that I, CLARENCE W. WITT, a citizen of the United States, residing at Wheeling, in the county of Ohio and State 5 of West Virginia, have invented certain new and useful Improvements in Laundry Tubs, of which the following is a specification, reference being had to the accompanying drawings.

10 This invention relates to certain improvements in laundry tubs, and it is an object of the invention to provide means whereby a plurality of tubs may be readily and conveniently supported by a portable frame or 15 structure whereby the assembled device is particularly adapted for use in home washings.

Another object of the invention is to provide a novel and improved structure of a 20 portable type and including a plurality of tubs and wherein one of the tubs may be readily employed as a boiler.

Furthermore, it is an object of the invention to provide a novel and improved structure which is particularly adapted for use 25 in connection with a washing machine and whereby the laundering operations may be materially facilitated and particularly as relates to the rinsing and boiling of the articles after being subjected to the action of 30 a washing machine.

The invention consists in the details of construction and in the combination and arrangement of the several parts of my improved machine whereby certain important 35 advantages are attained and the device rendered simpler, less expensive and otherwise more convenient and advantageous for use, as will be hereinafter more fully set forth.

40 The novel features of my invention will hereinafter be definitely claimed.

In order that my invention may be the better understood, I will now proceed to describe the same with reference to the accompanying drawings, wherein:—

Figure 1 is a longitudinal vertical sectional view taken through the device as herein embodied; and

50 Figure 2 is a sectional view taken substantially on the line 4—4 of Figure 1.

As disclosed in the accompanying drawings, S denotes a supporting structure comprising an upper frame F, preferably 55 long in form with its side and end members 1 consisting of angle irons. Coating with the corner portions of the frame F are the

vertically disposed supporting legs or standards 2. 3 denotes intermediate or central legs or standards coacting with said frame F. The legs 2 and 3 are suitably engaged with the frame F by the angle braces or brackets 4.

Secured to the lower portion of the legs 2 and 3 is the supplemental frame F', also oblong in form. The central portion of the 60 side members 5 of the supplemental frame F' are connected by the transversely disposed brace member 6 which also operates in connection with the intermediate or central legs 3. The central portion of the side 70 members 1 of the frame F are also connected by the transversely disposed bracing member 7. The central or intermediate legs 3 at a point substantially midway between the transverse members 6 and 7 are also connected by an additional bracing member 8.

The members 6, 7 and 8 substantially divide the supporting structure S into two separable compartments a and b and in which is movably positioned the tubs T and 80 T'. Each of the tubs T and T' has its upper marginal portions defined by the outstanding flanges 9 which rest upon the adjacent side and end members 1 and the upper transverse member 7 whereby said tub is 85 properly suspended and maintained in applied position within its compartment.

In practice, it is preferred that each of the tubs T and T' be formed of either sheet copper or galvanized iron with the outer 90 faces thereof coated with a suitable paint. In the present embodiment of my invention, the bottom 10 of each of said tubs is substantially semi-cylindrical in cross section. In communication with each of said tubs 95 through the lowermost portion of the bottom 10 and adjacent an outer end thereof is a depending pet cock 11 whereby the water within such tub may be readily drained therefrom. By having the tubs T and T' 100 removably engaged within their compartments a or b, either of said tubs can be readily replaced after becoming unduly worn or otherwise unfit for use. Coacting with the upper or open face of each of the tubs 105 T and T' is a lid or cover member L, having one marginal portion hingedly connected, as at 12, with a side member 1, said hinged connection 12 being such that, when desired, the lid L may be swung into a position to 110 overlie a side of the structure S so that when the lid L is so positioned, the assem-

bled device will occupy a minimum of space.

Connecting the side members 5 of the supplemental frame F', at a point substantially midway of the compartment a, are the transversely disposed members 14 in relatively close proximity one to the other and which serve as supports for a heating unit H and which unit preferably comprises a conventional type of gas stove, although it is to be understood that the same may be an oil burner if preferred. By the use of the heating unit H, the tub T within the compartment a can readily be employed as a boiler not only for use in boiling clothes or kindred articles but to provide a source of hot water in relatively large quantities and particularly for use in connection with a washing machine.

In practice, my improved device, as herein disclosed, is adapted for use as an accessory to a washing machine. When the articles are taken from the washing machine, they are wrung or otherwise delivered into the tub T and rinsed into the tub T'. In view of this, it will be readily seen that my improved device permits the washer to be kept going while the rinsing is being done so that the complete washing operation is materially facilitated. It will also be understood that the articles of clothing or the like, when required, can be readily boiled within the tub T and which tub primarily serves as a boiler. Furthermore, the capacity of the tub T is such to permit a sufficient quantity of water to be properly heated before being put into the washing machine. This is of decided advantage because in ordinary homes the water boilers are generally not of sufficient capacity to furnish the requisite supply of hot water. By having the pet cock or spigot 11 heated water within the tub B can be readily withdrawn with a minimum of effort and without the liability of the water being spilled upon the floor.

When my improved device is not in use and with the lids L in closed position, the device can be readily employed as a table and by having the structure S portable, the

device is particularly adapted for use in the household. To facilitate the desired transportation of the device, the lower ends of the legs 2 and 3 are provided with the casters 15 of any ordinary or preferred type. Furthermore, my improved apparatus when not being employed in connection with a laundering operation, can be readily employed for other uses and particularly as a clothes hamper or to soak the wash before being applied to a washing machine. Furthermore, either of the tubs T or T' can be readily employed for hand washing when it is not desired to employ a washing machine.

It is also to be understood that either of the lids L can be supported in substantially a horizontal position to serve as a table upon which to place articles of a wash and particularly after being removed from the rinsing tub T'.

From the foregoing description, it is thought to be obvious that a machine constructed in accordance with my invention is particularly well adapted for use by reason of the convenience and facility with which it may be assembled and operated, and it will also be obvious that my invention is susceptible of some change and modification without departing from the principles and spirit thereof and for this reason, I do not wish to be understood as limiting myself to the precise arrangement and formation of the several parts herein shown in carrying out my invention in practice except as hereinafter claimed.

I claim:—

In combination, a portable structure comprising vertically spaced frames, a tub freely insertible through the upper frame, the upper marginal portions of the tub being defined by outstanding flanges contacting with the frame whereby the tub is supported in applied position, a cover for said tub, and means for hingedly connecting said cover with one of the members of the upper frame.

In testimony whereof I hereunto affix my signature.

CLARENCE W. WITT.
